US00D607852S

(12) **United States Design Patent**
Riede

(10) **Patent No.:** **US D607,852 S**
(45) **Date of Patent:** **** Jan. 12, 2010**

(54) **COMMUNICATION CONTROLLER**

(75) Inventor: **Steven Riede**, Long Beach, CA (US)

(73) Assignee: **Magnadyne Corporation**, Compton, CA (US)

(**) Term: **14 Years**

(21) Appl. No.: **29/313,286**

(22) Filed: **Dec. 23, 2008**

(51) **LOC (9) Cl.** **13-03**

(52) **U.S. Cl.** **D13/174; D13/171**

(58) **Field of Classification Search** **D13/107, D13/144, 162, 171, 174; 174/66; 200/5 R, 200/5 A, 1 B, 293, 296, 329, 406, 513, 520, 200/530, 302.1, 302.2, 314, 315, 341, 344; 315/291-296; 338/198-200; 307/10.1**

See application file for complete search history.

Primary Examiner—Selina Sikder

(57) **CLAIM**

The ornamental design for a communication controller, as shown and described.

DESCRIPTION

FIG. 1 is a perspective view of the communication controller showing my new design; and,

FIG. 2 is a front elevational view thereof.

The broken lines in the drawings depict environmental subject matter only and form no part of the claimed design.
